UNITED STATES PATENT OFFICE.

CHARLES Q. REYNOLDS, OF ST. LOUIS, MISSOURI, ASSIGNOR TO LORENZ MUTHER, OF NEWTON, MASSACHUSETTS.

SKIVING MACHINE.

Application filed May 22, 1922. Serial No. 562,624.

To all whom it may concern:

Be it known that I, CHARLES Q. REYNOLDS, a citizen of the United States, residing at St. Louis, State of Missouri, have invented a new and useful Improvement in Skiving Machines, of which the following is a specification, reference being had thereto to the accompanying drawings.

This invention relates to a guard for skiving machines, and is designed with special reference to skiving machines of the character shown in United States Letters Patent No. 220,906 to Amazeen, dated October 28, 1879, for leather skiving machines.

In the use of skiving machines of this type it has been found that, after the leather has been skived by the rotary cutter, it is liable to curve upwardly with a consequent possibility of being cut or injured by the rear portion of the cutting disk. To avoid this difficulty the constant attention of the operator is required, and he is obliged to direct with his hand that portion of the material which has been fed through the machine and skived, and to hold it down and away from the rear portion of the cutting member.

The main object of my invention is the provision of a guard so formed that the material, after being skived, will be deflected in a downward direction and away from the cutting member, thereby avoiding all possibility of the material being injured by the rear portion of the cutting member.

Another object of the invention is the provision of a guard of the character described, which is of simple and efficient construction and which is capable of attachment to existing machines, without requiring any changes therein.

Other objects of the invention will be more specifically set forth and described hereinafter.

In its preferred form my invention contemplates a guard, adapted to be attached to the under surface of the cutter, and of a form adapted to deflect the material in a downward direction after it has been cut or skived. Although my invention is designed with special reference to the Amazeen machine above referred to, it may be applied to various other machines of this character.

In the accompanying drawings illustrating one form of my invention, Fig. 1 is a front elevation of the operative parts of a

skiving machine of the construction hereinbefore referred to, showing a guard applied thereto and constructed in accordance with my invention; Fig. 2 is a bottom plan view of the operative parts shown in and looking upwardly in Fig. 1; and Fig. 3 is a central, vertical, sectional view of the cutter with a guard made in accordance with my invention applied thereto.

In the drawings showing one embodiment illustrative of my invention, 10 indicates a skeleton cutting disk, held in position on the end of a shaft 12 between a disk 14 secured to said shaft and an outer locking disk 16. The outer edge or periphery 18 of the latter disk 16 is bevelled and adapted to engage the bevelled inner edge of the cutting disk 10, and thereby hold the latter disk in fixed position against a flange 20 on the disk 14. A screw 22 threaded into the end of the shaft serves to hold the locking disk in place.

A feed roll 30, mounted on a shaft 32, cooperates with a feeding disk 36 carried by a shaft 38; the two shafts being substantially perpendicular to each other. The feeding portion 40 of the feed roll is slanted, and may be provided with diagonal corrugations or ribs to grip the material in the feeding operation.

Secured to a fixed part 42 of the machine by a screw 44 is a bracket 46 provided with a vertical slot 48 to permit of vertical adjustment. The bracket carries a work gage, comprising an elongated plate 50 and a spring bar 52. The plate 50 has a longitudinal slot (not shown), which permits it to be adjustably secured to the bracket by the screw 54, and the bar 52 is fastened to the plate 50 by a screw 56. The free end of the plate 50 is formed into a guide 57, curving downwardly and toward the operator; and the free end of the spring bar 52 projects beyond the end of the plate 50, being provided with a depending portion 58, having its forward face curved for holding down the material and guiding it.

The spring bar 52 is resilient, and to hold it downwardly, yet permitting it to yield when necessary, the plate 50 is provided with an upright, fixed screw pin 60, set in its end and passing loosely through a hole in the spring bar 52. A helical spring 62 is mounted on the pin 60, and bears against the spring bar 52 at its lower end and against a nut 64 at its upper end; which nut may be

turned in one direction or the other to compress or release said spring, and thereby adjust the pressure exerted by it on the spring bar. For adjusting the work holding portion 58 in a vertical direction, a headed screw 66 is threaded through the spring bar 52, its end engaging the top surface of the plate 50, and by turning this screw the spring bar may be raised and lowered in relation to the plate. A set nut 68 threaded on the screw 66 serves to hold it in adjusted position.

All of the foregoing parts are of old and well-known construction, and reference may be made to the patent Amazeen herein referred to for a more detailed description of the foregoing parts, their functions, and mode of operation.

The novel feature of my invention resides in the provision of a guard, which is so formed as to deflect the material after it has been skived in a downward direction and away from the cutting disk. The guard may be constructed in any suitable form which will so deflect the material, and one such form is shown in the drawings, comprising a guard 70 in the form of an inverted bell fastened to the under surface of the plate 16 which holds the cutting disk in operative position. Any suitable means may be provided for securing the guard in place, and one such means is shown, comprising a headed screw 72 threaded into the nut 22 mounted in the end of the cutting disk shaft 12.

In the operation of a machine, the material to be skived is fed in under the guide 57 between the feed roll 30 and the feed disk 36. The shaft 12 is set at an angle, so that the cutting disk lies in a plane slightly inclined to the plane of the feed disk, the difference between these two planes representing the slant of the edge of the material after it has been skived. The cutting disk is operated at a high speed, and the material is held up closely to its cutting edge by the corrugated portion 40 of the feed roll 30, and the body portion of the material is held downwardly away from the cutting edge by the depending portion 58 of the plate 50. As the material is fed forward, it strikes the guard 70 secured to the under surface of the cutting disk, and is deflected in a downward direction away from the cutting edge.

The deflecting action of the guard overcomes the natural tendency of the stock to

curl upwardly into contact with the rear edge of the cutting disk, and thereby prevents injury to the material. In order to secure this downwardly deflecting action, it is, of course, necessary that the guard should project an appreciable distance beyond the lower surface of the cutting disk, and the bell-shaped guard shown in the drawings is especially adapted to secure this action. The provision of such a guard has the added advantage of permitting the operator to give his entire attention to the skiving operation, without being obliged to hold the material downwardly after it has been skived. Furthermore, the guard shown is of simple form and can be applied to existing machines without involving any changes or additions, other than the cutting of a threaded hole in the screw 22 in the end of the cutting disk shaft. 75

It is to be understood that my invention is not to be limited to the precise form herein shown and described, since it may be embodied in various other forms, all within the purview of the following claims.

What I claim is:

1. A skiving machine having, in combination, a cutting disk, means located below said disk for feeding the material to be skived against the cutting edge of said disk and then underneath said disk and a bell-guard mounted on the under side of said disk for deflecting the skived material downwardly and away from the cutting edge of said disk. 90

2. A skiving machine having, in combination, a cutting disk mounted for rotation, means located below said disk for feeding the material to be skived against the cutting edge of said disk and then underneath said disk and a hollow bell-guard centrally mounted on the under side of said disk for deflecting said skived material downwardly and away from the cutting edge of said disk. 95

3. A skiving machine having, in combination, a cutting disk mounted for rotation, means on one side and off-center of said disk for feeding the material to be skived against the cutting edge of said disk and then by the said disk on the feeding side and a hollow bell-guard mounted on the feeding side of said disk for deflecting the skived material away from the said disk and its cutting edge. 100

In witness whereof, I hereunto set my hand this 17th day of May, 1922.

CHAS. Q. REYNOLDS.
